UNITED STATES PATENT OFFICE.

ALFRED W. PROCTOR, OF BROOKLYN, NEW YORK; GEORGIETTA H. PROCTOR ADMINISTRATRIX OF SAID ALFRED W. PROCTOR, DECEASED.

INTERNAL-COMBUSTION ENGINE.

1,209,495.

Specification of Letters Patent. Patented Dec. 19, 1916.

Application filed February 9, 1912. Serial No. 676,498.

To all whom it may concern:

Be it known that I, ALFRED W. PROCTOR, a citizen of the United States, and a resident of Brooklyn, in the county of Kings and State of New York, have invented certain new and useful Improvements in Internal-Combustion Engines, of which the following is a specification.

This invention relates to hydro-carbon engines, particularly for burning fluids other than highly volatile liquids like gasoline or alcohol, and further relates to the provision of an improved cycle, thermodynamically correct, and theoretically known as the Joule cycle, in a practical engine.

Fuels having a high heat value can be had at less than the cost of gasoline, and being less dangerous are particularly advantageous for use in motor trucks where economy and safety are particularly important. In co-pending application Serial No. 660,749 filed Nov. 17th, 1911, there is described a transmission system for a motor truck which permits the use of a very inelastic motor, that is to say a motor having a constant speed. In the present application I have set forth an improved engine or motor which is particularly designed for motor trucks where high elasticity or flexibility in the engine is not required, as for example with systems employing my transmission referred to. Of course the improved engine is not limited to this field.

Primarily the invention contemplates the spraying of a fuel oil into a current of strongly compressed strongly heated and rapidly moving air at the instant such air is passing into a highly heated chamber. This chamber is arranged to withstand a high temperature without wear from the attrition of any mechanical parts which rub together while hot and unlubricated, which has been a source of difficulty in many prior constructions. Moreover any carbonization in this chamber will not be productive of difficulties as has been the case with some prior constructions. In the ordinary Diesel type engine the compression is carried to about thirty atmospheres or more at the limit of a compression stroke and thereupon heated by the injection of fuel oil. The compression of thirty atmospheres or more over a comparatively large piston area produces a tremendous strain on the engine bearings, the crank shaft, the wrist pin, the crank pin

and the connecting rod, and also on the engine frame, and the difficulties of getting sufficient rigidity are so great, that so far as I am aware the Diesel type engine has been limited to large and very heavy power units.

The present improved engine further contemplates the elimination of auxiliary devices to a great extent, and the use of valves is so improved and timed with accuracy to the movement of the pistons that there is no improper timing at high speed. Besides this it is further provided that the valves shall be very tight at the time of cut-off and lubricated against wear and excessive friction. In the interest of speed all the parts may have substantially harmonic or similar motion instead of abruptly controlled movements which are objectionable.

The engine is further designed to give two power impulses substantially 180° apart at each revolution thereby having substantially the effect of a four cylinder engine of the ordinary type. Besides this it aims to secure the advantages of compounding which are great where high pressure and temperatures are used.

The improved engine aims at the practically ideal or "Joule" cycle with a smooth and unbroken adiabatic expansion from the fuel cut-off pressure down to substantially atmospheric pressure. In this way the highest theoretical efficiency is obtainable.

The invention further contemplates the efficient prevention of leakage at the highest pressures. This is highly important where the engine is not of very large size and where the compression is high, since a large per cent. of a small highly compressed charge may escape through a very small crevice. The features of the invention by which leakage is prevented during the time of highest compression will appear hereafter.

With these various and other objects in view, the invention consists in the improved engine as hereinafter set forth.

In the drawings,—Figure 1, is a sectional and largely diagrammatic view showing an engine embodying the principles of the invention; Fig. 2, is a similar view showing a somewhat modified construction; Fig. 3, is a detail sectional view of an exhaust valve; Fig. 4 is a section on the section line of Fig. 3 looking in the direction of the arrow, and Fig. 5, shows a modification of the auxiliary compression cylinder.

Constructions embodying the invention will include a plurality of cylinders, preferably three of different bores and strokes of which one is a high compression cylinder receiving its charge from an auxiliary compression cylinder and delivering the charge after combustion and partial expansion during one working stroke into another cylinder where the expansion is continued until 10 all of the power of the charge is used up. The high compression cylinder where the combustion takes place presents particular features in its construction and use. The best constructions embodying the invention 15 will include a displacer in the form of a comparatively long cylindrical body 10 one end of which is connected to a plunger 11 within a chamber 12. I term this part 10 a displacer because it need not and does not 20 make a gas-tight fit in the cylindrical chamber where it moves. On the contrary the gases have a free passage from the lower side to the upper side of this member. Since this is true there is no need of having the 25 member 10 constructed like a piston, and it may in fact have a clearance on all sides so as not to touch the walls of the chamber at all. It may in fact be made of refractory material which is not adapted to resist frictional wear, but which would be serviceable 30 as a displacer, though not as a piston. The function of the displacer is solely to displace the gases on the lower side to the upper side when the displacer moves downward. The 35 plunger 11 moves up and down carrying the displacer with it. In this way the remote end of the displacer approaches and recedes from the end of its chamber 13 which may be termed the combustion chamber. This is 40 really a two part combustion chamber because the upper chamber 13 always has an open communication with the chamber 12. It is true the combustion does not take place in the chamber 12, because the air is not carbonized at this time, but except for this fact, 45 the chamber 12 is a part of the chamber 13. It may be observed at this point that the temperature in the combustion chamber may be very high and the walls are not expected 50 to be lubricated. The displacer will also become heated at this end and will expand and might bind in the chamber were it intended to be gas tight. Being merely a displacer however, it is not intended to be gas tight 55 and throughout a certain distance at the upper portion where it is hottest and least lubricated, it may, as above stated be slightly reduced in diameter so as not to even touch the wall of the combustion chamber. Of 60 course the distance of separation need only be a very small amount. Under these circumstances there is no difficulty from the heating of the combustion chamber.

I will now refer to some detail features of 65 this construction by which a very high com-

pression is retained in the combustion chamber, notwithstanding the presence of only a small charge. The only outlets from this combustion chamber are found at the sliding engagement of the plunger 11 with its 70 containing wall, and at the ports later described and at the outlet opening 16. I will now show a manner in which leakage may be guarded against through all of these exits from the combustion chamber. 75

First referring to the plunger 11, it will be seen that it has a reduced portion 17 which subsequently expands into another plunger or piston 18 which is of nearly but not quite the same diameter as the first 80 plunger 11. This constitutes a fuel pump. The space around the reduced portion 17 is a fuel oil chamber 19, and this chamber will normally be filled with the fuel oil. This oil is admitted and discharged from the 85 chamber through check valves 20 and 21. Below this chamber the piston 18 is very carefully constructed and packed. Being of small diameter, and always cold or at an unvarying temperature, and above all only 90 holding oil pressure instead of air pressure, the leakage past this piston can be almost entirely provided against. I have illustrated a cup leather washer 22 in addition to a series of packing rings 23. This arrangement will easily hold five hundred pounds of oil pressure without leakage. If there is any leakage it will be only a few drops of oil which can be collected without waste. Thus the oil above this piston constitutes a seal and it does not matter whether the upper piston or plunger 11 is packed or not, since the oil pressure in the chamber 19 is always the same as the air pressure in the chamber 12 and in the combustion chamber 13. It will be observed that these conditions prevent any escape of air from the combustion chamber past this piston or through the fuel oil passage 25. It will now be shown that the escape of air through an inlet port 26 and a lubricating port 27 and an outlet valve 16 is guarded against in the best constructions embodying the invention. 100

Referring to the inlet port it will be noted that the displacer 10 in moving downward moves across and cuts off the inlet port 26. The displacer is comparatively cold at this end where it may be surrounded by water jackets 29. In order to hold the displacer in contact with the wall and make it in effect a perfect slide valve, spring bearers 30 may be inset in the lower part of the displacer 10 which keep it thrown over toward the left in Fig. 1. Immediately therefore that the displacer has traveled across the open port 26 the latter is closed and it will be presently shown that at this instant the pressure in the passage 26 falls, while that in the combustion chamber is very high so 115 120 125 130

- that the air pressure holds the displacer firmly over the port 26 making a perfect slide valve or seal. The lubricating oil passage 27 is at the same time covered up, it being understood that lubricating oil will be fed during the interval of no pressure in the combustion chamber. The oil pipes 27 lead to any suitable oil tank, (not shown) from which the oil feeds by gravity. It is not necessary to have either pressure or check valve in this oil supply pipe because the pipe is always covered up by the wall of the piston 41. Furthermore, it will be observed that as both the air pressure and the spring 44 tend to keep the piston 41 pressed toward the right in the drawings, there will not be any leakage even although the cylinder wall and piston wear to a considerable extent. This is because the ports are all on one side, and the piston is kept borne against the cylinder always on this side. The only remaining outlet for the combustion chamber as shown in Fig. 1, is the puppet valve 16 which may be comparatively small and further kept cold by any suitable water jacket (not shown) and which can be frequently reground if desired, but which is not subject to severe erosion on account of the fact that the hot gases never flow past its surface at very high velocity. Since this valve constitutes the only real possibility of leakage, it can be readily watched and will not be found in practice to cause trouble as a practical proposition. Of course lubrication of the surface of a puppet valve is unnecessary and none is provided for, the temperature being exceedingly high.
- By the foregoing arrangement the hot and highly compressed gases are made effective to drive down the displacer 10. It will be understood that at the first part of the downward stroke of the displacer a body of highly compressed uncarbureted air is in the chamber 12 below the displacer 10 and as the displacer moves downward this compressed charge is driven upward through a passage 32 at one side of the displacer or in the stationary wall (see Fig. 2). As this air shoots upward it meets the fuel which is being displaced from the chamber 19 on account of the contraction of volume of this chamber. The amount of this fuel is regulated to the right amount for the charge of air supplied. The air being intensely compressed and thus heated by the compression and further heated by the hot chamber 13 into which it flows will at once atomize and largely vaporize the fuel and ignite the same and the fuel will burn during the entire period that the displacer is moving downward, or in other words during this power stroke. The gas pressure will rise considerably in the chamber 13 due to the fact that the already highly compressed gases are greatly heated by the combustion. It is true that there is a certain expansion during this combustion in the chamber 13. This expansion may be so great as to prevent any substantial increase of pressure at this time, if desired. The expansion is equal in amount to the volume displaced by the movement of the piston 11. If this piston is large and the stroke long, the expansion will be considerable, but if on the other hand the piston is small and the stroke short, the expansion will be much less. Most of this expansion goes into the power stroke, and the power is considerable from this source as the pressure is very high. Not all of the power goes into the power stroke however, and a part is absorbed in compressing the fuel in the chamber 19. As a matter of fact the amount of force which goes into the power stroke is proportional to the diameter of the lowest piston 18 rather than the middle piston 11, for the reason just mentioned. The pressure will however rise continuously in most cases, the volume expansion being insufficient to prevent such rise.
- At substantially the conclusion of the downward stroke the valve 16 will open and the compressed and partially expanded charge will flow into the low pressure cylinder 35 in which the piston 36 is at this instant in the extreme top of the stroke. It is desirable that this piston have as small clearance at the head end as possible, and this may be made as small as desired by having the piston fit well against the cylinder head. Thus when the valve 16 opens there is no erosion of its surface, but simply a continuing drop of pressure and a moderate flow of the gases during the next 180° of crank rotation, while the charge is expanding to its limit in the large cylinder 35. At the conclusion of this latter stroke, the exhaust 37 opens and the inlet valve 16 closes. The expansion will have nearly reached atmospheric conditions by this time and during the return stroke of the piston 36 the spent gases will be wholly expelled and the system thoroughly scavenged. It will be observed that the displacer 10 in the meantime has substantially expelled the charge from the high pressure cylinder. This is accomplished by the upward movement of the displacer 10 which reduces the combined volume of the chambers 12 and 13 to the same extent that this volume expanded during the power stroke. Inasmuch as the gases are at substantially atmospheric pressure during their final expulsion from the chambers 12 and 13, the residue remaining in the chamber 12 is inconsequential. It is vastly less in quantity than the working charge in these chambers under pressure.
- As a means of initially compressing the charge an auxiliary compression cylinder 40

may be provided and whose operation is such that when the piston 41 has compressed the charge to any point desired, a valve will open and admit this compressed charge into 5 the chamber 12, or in other words into the lower part of the combustion chamber. The further compression of the auxiliary piston 41 simply displaces or expels the compressed charge from this cylinder to the other. The 10 time at which the valve from the auxiliary compression cylinder opens of course determines the amount of compression obtained therein, and this in turn bears a relation to the volume of the high pressure cylinder. 15 In the drawings, for the purposes of illustration, the outlet of the auxiliary compression cylinder is shown opening at a crank position 45° short of its vertical limit. This angle may be diminished if desired or may 20 be increased somewhat. As a convenient means of exactly controlling the timing, the piston 41 may be made with a passage 42 having an outlet port 43 which registers with the passage 26 at the right instant. 25 This very exactly controls the timing and constitutes a means which is free from vibration and certain in its action at high speeds. A spring bearer 44 on the opposite side of the piston 41 keeps the latter pressed over 30 the port 26 like a slide valve, and the air pressure on the bearer side of the piston insures a gas tight fit at all times. The spring bearer 44 is simply for the purpose of keeping the surfaces lightly pressed together, the 35 air pressure furnishing the main force in this regard. The lubricating oil vent 45 is closed at the same time by this pressure, but will admit lubricating oil during the intervals of no pressure in this cylinder. The air 40 may be admitted through an inlet check valve 46.

Reference has been made to the fact that the ports 43 and 26 come into register at a certain angle short of the vertical position 45 of the crank. The low pressure piston 36 is under these circumstances offset by this same angular distance from the bottom vertical position of its crank, or substantially so. To this extent therefore the high pressure 50 and low pressure systems are not 180° apart.

It will of course be understood that the details of the mechanism may be considerably varied. For example in place of the valve just described a gate valve 50 (see 55 Fig. 2) may be used, operated by a cam 51. In Fig. 2 certain details of the displacer have been omitted and the construction of valve operating mechanism of the low pressure cylinder modified. The gate valve 50 is shown operated by a rod and the cam 51. Likewise the exhaust valve is shown operated by an ordinary eccentric instead of the vertical shaft 54 as shown in Fig. 3. It will of course be understood that various 60 modifications such as these may be used

which do not depart from the essential spirit and scope of the invention. In Figs. 3 and 4 a plan of operating the valves of the low pressure cylinder is illustrated which has much positiveness of action and is 70 further adapted for high speeds.

A synchronously driven shaft 54 is provided with an eccentric roller 55 which runs in a yoke 56 having two arcuate portions 57 struck on separate centers so as to form a 75 shape like a cross-section of a double convex lens, rather than being exactly circular. Since the centers, just mentioned, on which these arcuate portions 57 are struck are rather close together, however, the difference 80 from a perfectly circular shape is not wide, being about as illustrated in Fig. 4 of the drawings. The result of the rotation of the roller 55 is to throw this yoke 56 with great 85 positiveness and abruptness to its extreme positions of movement at two intervals 180° apart. During the intermediate interval the yoke is positively held in extreme position. This yoke is simply attached to a valve rod 58 to which the valves 16 and 37 are 90 secured. Thus the valves 16 and 37 are opened and closed at the proper times and are firmly held securely on their seats during intermediate times. There is enough 95 elasticity in the yoke and in its support and in the shaft to get a perfect action. If desired the shaft bearing 60 may be made with a rubber or similar bushing 61 in the interests of a certain elasticity. The valves are of course held on their seats by the air 100 pressure primarily.

In operation it may be assumed that the displacer 10 is at the top of its stroke, the fuel chamber 19 at this time sucked full of oil, and the auxiliary compression piston has just arrived at the point of compression desired. At this time the puppet valve 16 is closed. During the next interval while the auxiliary piston 41 is reaching the top of its stroke, highly compressed air is passing 110 into the chamber 12 beneath the displacer 10 and this flow is cut off when the auxiliary piston 41 reaches the top of its stroke. At this instant the displacer reaches a position to close the port 26 and thus retain the pressure in the chamber 12. The further descent of the displacer 10 results in the transfer of the highly compressed and heated air through the passage 32 where it meets the fuel oil and atomizes and vaporizes the 115 same. The fuel is further ignited and burned and a high pressure is developed in both the chambers 12 and 13, which pressure is effective during a working stroke for substantially the entire downward movement of the displacer. At this instant the low pressure piston 36 reaches the top of its stroke and the valve 16 opens, the exhaust valve 37 simultaneously closing. The partly 120 expanded and intensely heated charge is now 125

free to expand further into the low pressure cylinder 35 which expansion continues until the end of the stroke of the piston 36. At this instant, which is 180° later, the valve 16 closes and the exhaust valve 37 simultaneously opens, remaining in this condition during the full return stroke of the piston 36 by which the exhaust gases are thoroughly scavenged into the waste pipe 63. In the meantime however, the auxiliary and high pressure cylinders have commenced a repetition of the cycle already described. In other words a new cycle will be gone through. In the foregoing action the power impulses are substantially 180° apart, the more powerful high pressure cylinder having a small crank and also a small diameter so as to avoid the tremendous strains referred to in the preliminary part of the specification.

Under these circumstances the high gas pressures can be easily controlled with a comparatively light and free running engine.

While the invention has been particularly described in a practical construction or constructions in such detail as to enable the same to be practically manufactured and used, it is not desired that the invention be particularly limited to this exact structure or structures since variations may be made without departing from its spirit and scope. For example in Fig. 5 a feature of the auxiliary cylinder is particularly illustrated and which is intended to practically eliminate end clearance during the compression stroke. It will be understood that an air compression cylinder should have a very small end clearance, particularly if it compresses the gases to a very high degree. Otherwise a considerable residual compressed charge is not utilized. In Fig. 5 the passage 42 is shown of conical or tapered form throughout and a corresponding cone or plug 64 exactly fills the tapered passage throughout its whole length at the end of the stroke. Thus there is theoretically no clearance at the end of the stroke although the passage 42 is open until the instant of the limit. This plug may be used to a less degree as shown in Fig. 1. With a similar purpose the port 26 may be made as straight and narrow as desired, amounting to a short narrow vertical slot joining the cavities of the respective cylinders. The control of the fuel oil may be effected in various ways, a governor operated by-pass valve 65 being illustrated. It is evident that the more the valve 65 is opened the less the fuel oil will be fed to the combustion chamber. Any suitable connection to any ordinary ball governor will open the valve 65 more or less. As a further means of regulation an additional valve 66 may be employed if desired. The valve 66 is merely a hand controlled valve of any sort, for example a gate valve, in the passage 25. When this passage is partly closed or throttled by the valve 66, a smaller fraction of the fuel will pass upward into the combustion chamber 32, and a larger proportion will pass outward through the overflow or by pass 65, to be collected for subsequent use again. This has the effect of making the power of the engine less.

With the form of displacer 10 shown in Fig. 1, it is desirable that a lateral movement be permitted independent of the plunger 11, and a joint 67 has been illustrated for this purpose. It will of course be understood that where connected valves 16 and 37 are employed the connecting rod 69 is as closely contained in a groove at the top of the cylinder 35 as may be, so as to diminish end clearance in this cylinder. The rod will simply be cut away enough at 70 to permit the flow of gases into and out of this cylinder.

What is claimed is,—

1. An internal combustion engine comprising an air compressor, a high pressure cylinder, a displacement piston therein, a low pressure cylinder, a passageway between the compressor and high pressure cylinder, a passageway between the high pressure cylinder and low pressure cylinder, an oil pump attached to displacement piston and adapted to pump oil into high pressure cylinder, and means adapted to open communication between high and low pressure cylinders at proper intervals.
2. An internal combustion engine comprising an air compressor, a high pressure cylinder, a displacement piston therein, a low pressure cylinder, a passageway between the compressor and high pressure cylinder, a passageway between the high pressure cylinder and low pressure cylinder, an oil pump, actuated to displace oil into the passageway between the compressor and the high pressure cylinder during the power stroke thereof, and means adapted to open communication between the high and low pressure cylinders, at proper intervals.
3. An internal combustion engine comprising an air compressor, a high pressure cylinder, a displacement piston therein, a low pressure cylinder, a passageway between the compressor and high pressure cylinder, a passageway between the high pressure cylinder and low pressure cylinder, an oil pump, means for actuating said oil pump during the power stroke to pump oil into the high pressure cylinder, and means adapted to open communication between high and low pressure cylinders at proper intervals.
4. An internal combustion engine comprising an air compressor, a high pressure cylinder, a piston therein, a low pressure cylinder, a passageway between the compressor and high pressure cylinder, a passageway between the high pressure cylinder

and low pressure cylinder, a crank shaft having crank connections with the various pistons, the low pressure cylinder having its crank position as much more than 180 degrees in advance of the high pressure crank, as the auxiliary pressure cylinder has its crank position behind the said high pressure crank, and means adapted to open communication between high and low pressure cylinders at proper intervals.

5. An internal combustion engine comprising an air compressor having a piston, a high pressure cylinder, a displacement piston therein, a low pressure cylinder, a passageway between the compressor and high pressure cylinder, a passageway between the high pressure cylinder and low pressure cylinder, said air compressor and displacement pistons mutually coöperating to control the 15 passage between the compressor and the high pressure cylinder, and means adapted to open communication between high and low pressure cylinders at proper intervals.

20. An internal combustion engine comprising an air compressor, a high pressure cylinder, a displacement piston therein, a low pressure cylinder, a passageway between the compressor and high pressure cylinder, a passageway between the high pressure cylinder and low pressure cylinder, said displacement piston having an upper

25 slightly reduced portion and a lower larger portion fitting the high pressure cylinder, said passageway between the compressor and the high pressure cylinder being controlled by the enlarged part of the displacer, and means adapted to open communications 30

35

between high and low pressure cylinders at proper intervals.

7. An internal combustion engine comprising an auxiliary compression cylinder, a piston therefor, said piston having a passage leading toward the crank end, a projection within the cylinder fitting said passage, a high pressure cylinder, a piston therein, a passageway between the compressor and high pressure cylinder, said passageway being controlled by the said pistons, a low pressure cylinder, a passageway between the high pressure cylinder and low pressure cylinder, and means adapted to open communication between high and low pressure cylinders at proper intervals.

8. An internal combustion engine comprising an auxiliary compression cylinder, a 55 check valve at the head end thereof, a piston having a passage leading toward the crank end, a high pressure cylinder, a piston therein, a passageway between the auxiliary compression cylinder and the high pressure cylinder and controlled by said pistons, an oil pump for injecting fuel during the power stroke into the high pressure cylinder, a low pressure cylinder, and means adapted to open communication between high and low 60 pressure cylinders at proper intervals.

Signed at New York, in the county of New York and State of New York, this 7th day of February, A. D. 1912.
